UNITED STATES PATENT OFFICE

JOHN WEBER, OF CHICAGO, ILLINOIS

LOCK

Application filed August 11, 1930. Serial No. 474,345.

The present invention relates to locks and its principal object is the provision of a door lock wherein a bolt may be provided with a rack bar to be operable by a gear.

5 A further object of the present invention is the provision of a lock of the character stated wherein bolt operating mechanism may connect with a suitable key mechanism to be operable by a specially designed key, in order that only the proper key may be inserted therein to operate the said bolt operating mechanism.

10 A still further object of the present invention is the provision of a lock which may be simple and durable in construction and efficient in operation.

15 With the above general objects in view and others that will appear as the nature of the invention is better understood, the same consists in the novel construction, combination and arrangement of parts hereinafter more fully described, illustrated in the accompanying drawings and pointed out in the appended claims.

20 In the drawings forming a part of this application, and in which like designating characters refer to corresponding parts throughout the several views,

25 Fig. 1 is a cross-sectional view on a horizontal plane through the door-frame and the door, showing a top plan view of the lock;

30 Fig. 2 is a plan elevational view of the lock, when the same is removed from the door showing the side adjacent the door;

35 Fig. 3 is a cross-sectional view through the lock casing, the view having been taken on line 3—3 of Fig. 1;

40 Fig. 4 is a transverse cross-sectional view through the lock and key casing, the view having been taken on line 4—4 of Fig. 2 and substantially along line 4—4 of Fig. 3;

45 Fig. 5 is a transverse cross-sectional view on line 5—5 of Fig. 3;

50 Fig. 6 is a transverse cross-sectional view through the key casing on line 6—6 of Fig. 4;

55 Fig. 7 is a cross-sectional view through the key casing on line 7—7 of Fig. 4; and

60 Fig. 8 is a side elevational view of a revolving plug in the key casing.

Referring in detail to the present drawings there is shown therein casing 10 which is substantially rectangular in cross-section. The upper wall of said casing, and substantially centrally thereof, is provided with a semi-circular bulge providing housing 11 for the bolt operating mechanism which will be hereinafter described. Adjacent the rear side of said casing 10 the lower and upper walls of said casing are provided with flanges 12 and 13, the latter flange merging with the semi-circular wall of housing 11, as seen on Fig. 1.

65 The invention further includes plate 14, which is provided at its edge and at its rear face with molding 15. A number of screws 16 passing through said molding 15 attach said plate 14 to flanges 12 and 13.

70 Positioned upon the lower wall of said casing 10 and adjacent the rear portion thereof and adapted for longitudinal movement within said casing 10 is bolt 17, which may project through both ends of said casing 10. At the upper edge said bolt is provided with rack 18 with which shaft gear 19 is adapted to mesh. Said shaft gear 19 is integrally formed with shaft 20, whose two ends are set within plate 14 and the front wall of casing 10, as clearly seen in Fig. 5. Adjacent the front plate of casing 10 said shaft 20 carries gear 21 which meshes with gear 22 upon shaft 23. One end of said shaft 23 is positioned within the front plate of casing 10 for rotation, while the opposite end thereof extends through plate 14 and terminates in an enlarged head 24. Interposed between bolt 17, plate 14, and the lower wall of casing 10 is angle plate 25 made of brass or other like soft metal for reducing friction and permitting easy sliding movement for bolt 17.

90 Contacting with plate 14 and receivable within the space defined by molding 15 is plate 26 which has projecting from one side thereof cylinder 27 which is riveted as at 28, or by any other suitable means attached to said plate 26. Receivable within said cylinder 27 is a rotatable plug 29 which extends substantially to the enlarged head 24 of shaft 23. Said cylinder 27 has its periphery recessed at two spaced points for receiving 100

therewithin substantially segmental or crescent-shaped plates 30 which are frictionally held within recesses made in the cylinder 27, the outer peripheries of said crescent shaped plates 30 remaining flush with the periphery of cylinder 27, as clearly seen on Figs. 4 and 6. The inner peripheral portions of said crescent shaped plates 30 enter within grooves 31 made circumferentially in said rotatable plug 29. The inner peripheral portions of said crescent shaped plates 30 are freely positioned within grooves 31 permitting free rotary movement of said revolving plug 29, at the same time preventing any longitudinal shifting movement of said revolving plug 29 within cylinder 27.

Said revolving plug 29 is provided with a longitudinal slot 32, one edge of which begins slightly beyond or near the axial center 20 of said revolving plug 29, and the other edge reaches to the periphery of said plug. Said crescent shaped plates 30 adjacent their centers and at the inner peripheries thereof have notches 33 which are adapted to register with slot 32 in order that key 34 may be inserted.

Interposed between the inner end of the revolving plug 29 and head 24 and set by its wing portion and tooth 35 within cylinder 27 is plate 36 having central opening 37. Said plate 36 centrally of its wing portion 34 and in alignment with tooth 35 has notch or slit 38 which is in alignment with notches 33 of the crescent-shaped plates 30, and which registers with slot 32 when revolving plug 29 is set in proper position for insertion of key 34. It is to be observed that the inner periphery of plate 36 remains at a plane which is nearer to the center of cylinder 27 than the inner peripheries of the crescent shaped plates 30 for the purpose which will be presently mentioned.

Key 34 at one of its edges is provided with two recesses 39 registering with the crescent-shaped plates 30. Adjacent one of its ends 45 said key 34 is provided with another recess 40 registering with washer plate 36 when the key is in operative position within slot 32 of the revolving plug 29. By virtue of the fact that the inner periphery of the washer plate 36 is nearer to the center of cylinder 27 than are the inner peripheries of the crescent-shaped plates 30, recess 40 is necessarily deeper than recesses 39. Thus, by varying the width of said crescent-shaped plates 30 and 50 washer plate 36, and consequently the depth of recesses 39 and 40 of the key, locks may be constructed requiring different keys.

Positioned upon said cylinder 27 and frictionally held thereupon is barrel 41 having 60 at its front end inwardly extending flange 42, the inner periphery of which remains in alignment with the inner periphery of said cylinder 27, the outer end of said cylinder 27 contacting with the inner face of said flange 65 42, as clearly seen on Fig. 4. Extending

through said flange 42 and remaining flush with the outer face therewith is the outer end of the revolving plug 29, as seen on Figs. 2 and 4.

Head 24 is provided with a longitudinal 70 slot 43, which normally remains in alignment with notches 33 and 38 of the crescent-shaped plates 30 and washer plate 36, respectively, for receiving therewithin the end of key 34 for the purpose hereinafter described.

At the lowermost point at the periphery of barrel 41 and adjacent plate 26, a housing 44, including bottom wall 45, is provided, the walls of said housing 44 being in any suitable manner affixed either to said barrel 41 or to said plate 26 or to both. Receivable within said housing 44 is a plunger pin 46, adapted to enter into an opening made in cylinder 28 and adapted to enter and extend into slot 43 of head 24. The opposite end of said plunger pin 46 is provided with head 47 adapted to shift within said housing 44 and within the registering opening made in the body of barrel 41. Interposed between said head 47 and bottom wall 45 of said housing 44 is a coil spring 48 urging said plunger pin 46 towards and into slot 43.

When key 34 remains out of position within slot 32 and slot 43, as shown in Fig. 4, the plunger pin 46 remains within said slot 43 95 and thus prevents any rotary movement of head 24 and shaft 23. The end of the key, which may be slightly tapered at the point of the first engagement thereof with the end of the plunger pin 46, as the same enters into said slot 43, is adapted to displace said plunger pin 46 from said head 43 and drive the same inwardly of housing 44 against the tension of spring 48. As soon as this is accomplished, key 34, by virtue of its engagement with head 24, will be adapted to rotate shaft 23. The rotary movement thus imparted to shaft 23 and its gear 22 will be transmitted to gears 21 and 19 upon shaft 20. The rotating gear 19 upon said shaft 20 will shift bolt 17 into locked or unlocked position with respect to the keeper plate 49 and its head 50 which is provided with opening 51 for receiving the adjacent end of bolt 17. Of course, the movement of bolt 17 into one or the other direction depends upon the direction of turning of key 34, head 24 and shaft 23.

Said plate 49 is affixed by a plurality of screws 52 to wall 53. To conceal said plate 49 door-frame 54 may be placed upon said plate 49.

As is apparent from the hereinabove description, plate 26 is not in any way permanently attached to casing 10 or its plate 14. As was said, said plate 26 is receivable within space defined by molding 15. Likewise head 24 of shaft 23 is adapted to freely enter cylinder 27 at its inner end. As said head 130

24 is inserted within said cylinder 27, plunger pin 46 freely enters slot 43.

To place the lock upon door 55 opening 56 is made therein for positioning therewithin 5 barrel 41. Likewise suitable space is scooped out from the body of the door to accommodate housing 44. When said housing 44 and barrel 41 are in position within opening 56 of door 55, and plate 26 contacts with the adjacent 10 face of the door, screws 57 are passed through said plate 26 and driven into door 55. Thereupon casing 10, including plate 14, is positioned upon said plate 26, and preparatory thereto head 24 is shifted within 15 cylinder 27. Thereupon screws 58 are passed through registering openings made in flanges 12 and 13, plate 14 and its molding 15, and thereupon said screws 58 are driven into the door 55. Thus, by this means plate 20 26 will be held in position with respect to plate 14 and its molding 15, as well as head 24 within cylinder 27.

It is to be observed that as long as suitable 25 and proper key is not inserted within slots 32 and 43, it will not be possible to rotate head 24 and shaft 23 for shifting bolt 17 in either direction, because plunger pin 46 remaining within slot 43 prevents rotary movement of head 24. As soon as said plunger 30 pin 46 is displaced from within said slot 43 and driven into housing 44 by a proper key, as hereinabove described, head 24 may be rotated, and the adjacent free end of said plunger pin 46 will ride upon the periphery 35 of head 24, which pin will not spring back into slot 43 until said slot 43 comes in alignment with said plunger pin 46 when brought to that position by key 34, and as soon as said key is withdrawn plunger pin 46 will spring 40 into slot 43.

It is further observed that the ends of casing 45 10 proper are constricted, the bottom and upper walls thereof contacting with bolt 17, thus keeping the same in position and preventing its lateral shifting movement.

While there is described herein a preferred embodiment of the present invention, it is nevertheless to be understood that minor changes may be made therein without departing from the spirit and scope of the invention as claimed.

What I claim as new is:

1. A lock comprising a casing, a bolt 55 slideable therein, a cylinder supported by and projecting rearwardly from one wall of the casing, bolt operating means including a shaft journaled within the casing and having a relatively large cylindrical portion received by said cylinder, a plug rotatably 60 mounted in said cylinder in end to end relation with said cylindrical portion of the shaft, said plug and cylindrical portion of the shaft having aligned key receiving slots, a housing surrounding said cylinder and including an offset portion, said cylinder and

cylindrical portion of the shaft having aligned openings, and a spring influenced key retractable pin supported within the offset portion of the housing and normally positioned in said openings to hold said shaft 70 against rotation.

2. A lock comprising a casing, a bolt slideable therein, a plate supported on the rear wall of the casing, a cylinder carried by the plate and projecting rearwardly therefrom, 75 bolt operating means including a shaft journaled within the casing and including a relatively large cylindrical portion received by said cylinder, a plug rotatably fitted within the cylinder in end to end relation with the cylindrical portion of the shaft, said plug and cylindrical portion of the shaft having aligned key receiving slots, said plug having spaced annular grooves, crescent shaped plates fitted in said grooves and having notches aligned with said key receiving slots, a housing surrounding said cylinder and having an offset portion, said cylinder and cylindrical portion of the shaft having aligned openings, and a spring influenced 90 key retractable pin supported within the offset portion of the housing and normally positioned in said openings to hold the shaft against rotation.

In testimony whereof I affix my signature. 95
JOHN WEBER.
